CLAIM

I claim the ornamental design for bread box, as shown and described in the drawings.

DESCRIPTION

FIG. 1 is a front elevation view of a bread box in accordance with the new design;

FIG. 2 is a side elevation view of the bread box of FIG. 1;

FIG. 3 is a rear elevation view of the bread box of FIG. 1;

FIG. 4 is a top plan view of the bread box of FIG. 1;

FIG. 5 is a bottom plan view of the bread box of FIG. 1;

FIG. 6 is a front isometric view of the bread box of FIG. 1; and,

FIG. 7 is a front isometric view of the bread box of FIG. 1 with the top open.
